UNITED STATES PATENT OFFICE.

RUDOLF LOEB, OF CAMDEN, NEW JERSEY.

SEWING-MACHINE.

1,187,074.

Specification of Letters Patent. Patented June 13, 1916.

Application filed January 14, 1913. Serial No. 741,948.

To all whom it may concern:

Be it known that I, RUDOLF LOEB, a citizen of the United States, and a resident of Camden, Camden county, New Jersey, have

5 invented certain Improvements in Sewing-Machines, of which the following is a specification.

My invention relates to sewing machines of the type employing a vibrating needle; 10 and the object of my invention is to provide means for regulating the extent of throw of the needle in order that I may produce stitches of varying length disposed transversely or substantially so to the general 15 line or direction of the ornamentation or embroidery produced by such stitches.

A further feature of my invention is the provision of a vibrating presser foot for use with such vibrating needle whereby 20 goods may be positively held against movement by the operator while the needle is in actual engagement therewith; passing in or out, as the case may be.

While I have shown my invention as applied to a machine employing a single 25 vibrating needle and a vibrating presser foot through which said needle passes, it will be understood that a plurality of vibrating needles, each provided with these parts, 30 may be employed without departing from my invention.

These and other features of my invention will be more fully described hereinafter, reference being had to the accompanying 35 drawings, in which:

Figure 1 is a side elevation of a sewing machine to which the improvements forming the subject of my invention have been applied; Fig. 2, is a plan view of the same; 40 Fig. 3, is an enlarged elevation of the needle end of the machine; with the cover plate removed; Fig. 4 is a side elevation, on the same scale, of that part of the structure shown in Fig. 3; Fig. 5, is a view similar to 45 Fig. 3, illustrating a modified construction within the scope of my invention, and Figs. 6 and 7, are perspective views illustrating details of my invention.

In the drawings, 1 represents the frame of 50 the machine; 2 the head, in which are contained the means for effecting vertical reciprocation of the needle-bar 3 which, in this type of machine is pivotally mounted at 4 so as to be capable of vibrating under 55 the action of suitable mechanism. In this connection, it may be noted that the mecha-

nism for imparting vertical reciprocation to the needle-bar is old and well known in the art, and no extended reference thereto will be made herein.

The needle-bar carries a needle of any ordinary or usual type, indicated at 5, which may be secured to said bar by a set screw 6, and said needle passes through a presser foot 7 carried by the end of said needle-bar and vibrating therewith. An enlarged view of the presser foot is shown in Fig. 6, and this member comprises a sleeve 8 encircling the needle-bar which is slotted at 9 for the passage of a cotter pin 10 to retain 70 said presser foot in place; the needle bar being hollow and having a spring 11 bearing upon said cotter pin so as to impart pressure to the presser foot and at the same time render the same yielding. The lower part 75 of the sleeve 8 is reduced at 12 so as to offer as little obstruction as possible to the viewing of the stitching operation, and the reduced portion is cut away at one side to admit the thread to the needle. The sleeve 80 is also slotted at 13 for the passage of the set screw retaining the needle in place.

In the lower part of the head of the machine an arm 15 is pivoted at 16, having a sleeve 17 pivoted thereto at 18; said sleeve 85 encircling the said needle-bar and through which said needle-bar may slide during its vertical reciprocation. Movement imparted to the arm 15 effects vibration of the needle-bar, and the needle and presser foot attached thereto through the pivotal arrangement noted, and an important part of my invention relates to the means for imparting movement to said arm whereby said needle-bar and its attached parts may be vibrated, 90 and the means for adjusting the extent of such movement.

To this end, the following mechanism may be employed: Suitably carried by the frame of the machine is a countershaft 20, 100 having a gear wheel 21 which receives motion from a gear wheel 22 on the main shaft 23 of the machine. On the opposite end of the countershaft is a cam 24, with which engages a roller 25 carried by an arm 26 connected to a rock shaft 27 suitably journaled in or on the frame of the machine, and having at one end a substantially yoke-shaped lever 28, one end of which engages with a pin 29 adapted to slide in a block 30 and impinge upon the arm 15. The yoke-shaped lever is provided with adjustable screws 31

and 32 forming contact points; said screws having lock nuts 33 whereby they may be retained in their adjusted positions.

Return movement of the arm 15 when the 5 roller-carrying arm 26 is released from the action on the high side of the cam is imparted by means of a flat spring 35, suitably connected to the head of the machine and having an end 36 bearing against the arm 15. Upon rotation of the countershaft, 10 movement is imparted to the cam and transmitted to the arm 15 for vibrating the needle-bar and its attached parts by the means just described; reverse movement being accomplished by the spring referred to. The extent of movement of the bar by the 15 cam and roller arm is determined by the size of said cam, while the position of the needle-bar, needle and presser foot with respect to the slot in the stitch plate is determined by the adjusting screws 31 and 32; 20 one being set in and the other out, as the case may be, and the upper one bearing upon the frame of the machine. I may provide, however, other means for effecting this result, as shown in Fig. 5, in which a roller arm 26^a is loose upon the rock shaft 27 and is arranged for connection with a slotted arm 40 carried by said rock shaft and secured thereto; said arm being preferably provided with a scale adjacent the slot with a set screw 41 carried by said roller arm whereby the parts may be connected together when the desired adjustment has been 35 made. In other respects, the structure and its operation is the same.

Vibrating feet as ordinarily employed for sewing machines move the goods. The vibrating foot forming part of my invention 40 is intended, however, for a different purpose, inasmuch as the movement of the goods is entirely under the control of the operator, and the function and purpose of such vibrating presser foot is to hold the goods 45 against such movement while the needle is in the goods. When the needle is out and the needle-bar raised, pressure upon the presser foot is relieved, and the operator can impart movement to the goods during the 50 momentary periods when the needle is lifted clear of the same.

It may be desirable at some times to position the needle with respect to the stitch plate so that it vibrates toward the front or 55 toward the rear, and this is accomplished by regulating the adjustable contact points 31 and 32 carried by the yoke-shaped lever one of which bears upon the pin engaging the arm 15 to vibrate the needle.

With my improved form of vibrating needle and vibrating presser-foot, I employ 60 a reciprocating shuttle which is operated for proper coordination with the needle in its various movements through the stitch plate. 65 As indicated in the drawings, my improved

needle-bar swings from the top of the head of the machine so that the arc included in the range of movement is very flat.

The needle in its vibratory movement swings toward the operator and the goods 70 may be moved back and forth independently of the movement of the needle and faster than its movements whereby stitches varying in length may be placed over the design to form a filling, body, or background, as 75 may be desired; such stitches varying in length, depending upon the extent of movement imparted to the fabric stretched in the tambour frame by the operator. When this filling is accomplished, the figure of 80 the design—flower or whatnot—can be outlined by causing the needle to lay stitches along said outline while the tambour frame is gradually moved by the operator bringing the said outline in proper position for 85 the stitches to be laid by the needle. In such action, the movement of the frame is relatively slow so that the needle moves faster than the goods and the outline stitches are substantially the same length, although the 90 line formed thereby may vary in thickness, depending upon the angle of movement imparted to the goods with respect to the plane of movement of the vibrating needle. In all instances, the character of work produced by 95 the needle is varied by the ratio of movement of the goods carried by the tambour-frame to the movement of the needle.

I claim:

1. The combination, in a sewing machine, 100 of a reciprocating needle-bar, a needle, means for driving the same, a main shaft, a countershaft driven therefrom, a rock shaft operated by the countershaft, means carried by said rock shaft for imparting 105 movement to the needle-bar in one direction, and means for moving said needle-bar in the opposite direction.

2. The combination, in a sewing machine having a reciprocating needle and means for 110 driving the same including a main shaft, of a countershaft driven from said main shaft, a rock shaft, a cam on the countershaft, an arm on the rock shaft engaged by the cam, means carried by said arm for imparting 115 vibrative movement to the needle in one direction, and means for moving said needle in the opposite direction.

3. The combination, in a sewing machine, 120 of a reciprocating needle-bar, a needle carried thereby, means for driving the same, a main shaft, a countershaft driven from the same, a rock shaft, a cam on the counter-shaft, an arm on the rock shaft engaged by the cam, means carried by said rock shaft 125 for imparting vibrative movement to the needle-bar in one direction, and means for moving said needle-bar in the opposite direction.

4. The combination, in a sewing machine, 130

of a reciprocating needle-bar, a needle carried thereby, a presser-foot carried by said needle-bar, means for driving said needle-bar and presser-foot in the formation of 5 stitches including a main shaft, a counter-shaft driven therefrom, a rock-shaft operated by the countershaft, means carried by said rock-shaft for imparting vibrative movement to the needle-bar and the presser- 10 foot carried thereby in one direction, and means for moving said parts in the opposite direction.

5. The combination, in a sewing machine having a reciprocating needle-bar, a pivotal 15 connection for the same whereby it may swing in addition to its vertical reciprocation, a needle carried by said needle-bar, a main shaft and means for driving the needle-bar from said main shaft, of a counter-shaft, 20 a rock-shaft driven from said countershaft, adjustable means carried by said rock-shaft for imparting vibrative movement to the needle-bar in one direction, and means for moving said needle-bar in the opposite direction. 25

6. The combination, in a sewing machine having a reciprocating needle-bar, a pivotal connection for the same whereby it may swing in addition to its vertical reciprocation, 30 a needle carried by said needle-bar, a main shaft and means for driving the needle-bar from said main shaft, of a presser-foot carried by said needle-bar, a countershaft, means for driving the same from the main 35 shaft, a rock-shaft, a cam on the countershaft for actuating said rock-shaft, means carried by said rock-shaft for imparting vibrative movement to the needle-bar and presser-foot in one direction, and means for 40 moving said needle-bar and presser-foot in the opposite direction.

7. The combination, in a sewing machine, of a reciprocating needle-bar, a pivotal connection for the same whereby it may swing

in addition to its vertical reciprocation, a 45 needle, means for driving the same, a main shaft, a countershaft driven therefrom, a rock shaft operated by the countershaft, means carried by said rock shaft for imparting vibrative movement to the needle-bar in one direction, and means for moving 50 said needle-bar in the opposite direction.

8. The combination, in a sewing machine, of a reciprocating needle-bar, a pivotal connection for the same whereby it may swing 55 in addition to its vertical reciprocation, a needle carried by said needle-bar, means for driving the same, a main shaft, a counter-shaft driven therefrom, a rock shaft, a cam on the countershaft, an arm on the rock 60 shaft engaged by the cam, and means for imparting vibrative movement to the needle-bar in both directions, one portion of said means being directly controlled and operated by said rock shaft and the other portion 65 of said means being independent of said rock shaft.

9. The combination, in a sewing machine, of a reciprocating needle-bar, a pivotal connection for the same whereby it may swing 70 in addition to its vertical reciprocation, a needle carried by said needle-bar, means for driving the same, a main shaft, a counter-shaft driven from the same, a rock shaft, a cam on the countershaft, an arm on the rock 75 shaft engaged by the cam, means carried by said rock shaft for imparting vibrative movement to the needle-bar in one direction, and means for moving said needle-bar in the opposite direction. 80

In testimony whereof, I have signed my name to this specification, in the presence of two subscribing witnesses.

RUDOLF LOEB.
